UNITED STATES PATENT OFFICE.

EDMUND M. WISE, OF CINCINNATI, OHIO.

SHOCK ABSORBER.

SEARCHED

Application filed March 18, 1922. Serial No. 544,940.

To all whom it may concern:

Be it known that I, EDMUND M. WISE, a citizen of the United States, residing at Cincinnati, in the county of Hamilton and State of Ohio, have invented certain new and useful Improvements in Shock Absorbers, of which the following is a specification.

My invention relates to improvements in shock absorbers and it more especially consists of the features pointed out in the annexed claims.

The purpose of my invention is to provide a simple and efficient shock absorber for automobiles that automatically damps out oscillations which may be due to road conditions, inequalities etc., which are either above or below the general contour of the road without increasing the initial disturbance under any circumstances. With most of the shock absorbers now on the market the initial disturbance due to inequalities etc., in the road may actually be increased by the shock absorber.

With these and other ends in view, I illustrate in the accompanying drawing such instances of adaptation as will disclose the broad underlying features without limiting myself to the specific details shown thereon and described herein.

Figure 1 is a side elevation of a shock absorber partly in section with the parts in a raised-axle position.

Figure 2 is an elevation in section of Figure 1 on the line 2-2.

Figure 3 is a plan view of Figure 1 in section.

Figure 4 is a detached diagrammatic view of the valves in the same position as shown in Figure 2.

Figure 5 is also a diagrammatic view showing the valves in an opposite position to that shown in Figures 1 and 4.

In attempts which have been made heretofore to overcome the excessive vibrations of motor cars dependence has been placed upon various forms of springs between the car body and the chassis, but in practice it has been found that while these do lessen shocks they do not control oscillations, in fact under many circumstances they actually accentuate these to the great discomfort of the passengers.

The disadvantages of placing entire dependence on springs has been recognized and a line of accessories developed which utilize

mechanical or hydrostatic friction to reduce oscillatory disturbances but at best these expedients leave much to be desired because they do not, in the main, reduce initial disturbances, but on the contrary rather accentuate them; that is they do not and by the nature of their construction cannot rapidly overcome one set of vibrations before being overtaken by another set on all sorts of roads.

A further disadvantage of previous proposals lies in the fact that an obstacle which raises a wheel above the normal road level produces quite a different effect from that produced by depressions such as chuck holes etc., in which a wheel is first "dropped" into the depression and then quickly raised out of it. Such devices are more especially designed for the bumps but they do not acquit themselves well in overcoming the effect of these and they do very badly when a succession of holes is encountered.

In practically carrying out my invention I may use whatever ratio of proportions, masses, etc., as may be demanded by the varying exigencies under which the device is operated, or the kinds of service it is found to be most adaptable to. The proportions of the several parts shown on the drawing may be varied at will to suit various circumstances.

The device in one form comprises a pump casing 12 which has a suitable annular flange to which a cover 13 is applied in any desired manner. The casing 12 forms a bearing for one of the trunnions 14 of a pump element and the cover 13 forms a bearing for the other trunnion 15. Cast integral with the trunnions, vanes 3 are formed. These function between the casing 12 and the cover 13 as motion is imparted to them from the car axle 20 through a link 19 and the arm 4, which latter is secured to the end of the trunnion 15. Thus as the axle rises or falls the arm 4 follows such movements.

The vanes 3 may be widened to any desired degree according to the class of service in which the "vibrake", as I call my device, may be used.

Within the casing 12 a mid-partition 16 is placed, as shown in Figure 1. It may be secured to the cover 13 by means of screws 17 so as to be removable with the cover, or it may be fastened in any other way. This partition serves to divide the chamber

within the casing 12 into interconnected parts, 1 with 1^a and 2 with 2^a in which oil is placed to be alternately acted on by the vanes 3, as the arm passes from its upward 5 to its downward position or vice-versa.

The casing 12 has a flange 21 and fastening ears 18. The latter serve to attach the vibrakes to the car frame in any convenient place near the car axles and adjacent 10 the wheels. The flange 21 forms a head against which an exterior casing 39 is seated. A series of projecting walls are formed on the head 21. Walls 23 enclose passages 5 and 7 and the inner walls 22 enclose a distributing chamber 6. These walls extend outward beyond a valve casing 27 at which point a central ball-valve fitting 40 is secured. This fitting has a neck or shoulder over which the conical end of the casing 39 15 passes. A nut 43 clamps the casing against the head 21 where it is aligned by a suitable flange on the outer side of the head.

Casing 39 within itself forms a storage oil chamber 42 from which oil is automatically drawn through passage 41 past ball valve 11 into or from the pump system to compensate for changes in temperature, leakage etc., though this latter will likely be 20 very small as the oil in the reservoir 42 will at all times be at about atmospheric pressure.

The control valve stem 8 carries two conical valves 25 and 26 secured thereon in any desired manner and spaced apart so that 25 when valve 25 is seated on its port in wall 22 closing access to passage 7 valve 26 is off from its seat leaving an opening from chamber 6 into the passage 5. The valve stem 8 has sliding bearing in the bushings 24 which are threaded into walls 23. Sufficient clearance is left at the ends of the stem 8, in the bushings 24 to permit of the necessary end movement of the stem to alternately close or open the valves 25 and 26.

45 An inertia valve 9 on stem 28 slides endwise in the casing 27. It cooperates with edges 31 formed in the wall of the casing 27 to form an opening from chamber 2 through passage 7 and opening 32 to chamber 6 past valve 26 into passage 5 and chambers 1 and 1^a shown in Figures 1 and 4 or from chambers 1 and 1^a through passage 5 and opening 33 into chamber 6 past valve 25 into passage 7 and chambers 2 and 2^a as shown in Figure 55. At each end of the stem 28 piston heads 29 are formed, these slide in the casing 28. A weight 35 is secured to the upper head 29 by means of a screw 36, and a compression spring 10 is placed within the hole 30 formed 60 throughout the length of the valve stem 28. This spring cooperates with the weight 35, to form a nearly balanced piston valve, secure a more sensitive movement of the valve 9, and hold it in mid position when not subjected to vertical acceleration. The area of

heads 29 in relation to that of valve 9 may be variously proportioned to suit different requirements.

A retaining plate 34 secured to the lower wall 23 holds the valve casing 27 in place. It may have a dowel pin that projects into the casing 27 in order to hold the ports 32 and 33 in alignment with passages 7 and 5 respectively. These passages may be formed round, by drilling if desired, instead of being cast in, and when formed a screw 37 for passage 7, and another, 38 for passage 5 75 cover the openings as shown in Figure 1.

The operation of the device is as follows: When the valve 9 is in the position shown 80 in Figures 1 and 4, oil will flow freely from chamber 2, (the arm 4 having been raised) through passage 7, opening 32, past valve 9 into chamber 6, past valve 26 into chamber 5 and finally into chambers 1 and 1^a above 85 and below the partition 16. Flow in a reverse direction will instantly close valve 26, and it can only continue through opening 33, when its pressure rises enough to open valve 9 when it will discharge into chamber 6, past valve 25 into chamber 7 and finally 90 into chambers 2 and 2^a.

A fundamental object of my invention is to reduce the disturbance of the body of the car with respect to space. This involves the 95 reduction of the vertical accelerations of the car. It must be emphasized that the action of the device is primarily determined by the vertical accelerations and displacements of the car body with respect to space.

When the axle movement with respect to the car frame and the frame accelerations are upward, the arm 4 will move upward freely but downward with difficulty. In the device instanced the force required to 105 move the arm 4 will depend directly upon the vertical acceleration of the car frame, it being assumed that the movement of the arm with respect to the car frame is in a direction opposite to the acceleration of the 110 frame itself; the force required to move arm 4 in the direction of the acceleration of the car frame in any case is small, and reverse accelerations will obviously reverse all of the functions of the device.

It may be desirable to modify the action of the device so that force required to move the arm 4 would be independent of the magnitude of the vertical acceleration of the car body. This acceleration is the only 115 factor which determines the direction in which arm 4 will exert a force in opposition to the movement. From this it will be seen that the secondary effect is suppressed and oscillations are rapidly damped.

The pressure to move the valve 9, in both directions, is produced by the vane 3 forcing the oil from either chamber 1 or 2 into passage ways 5 or 7 so that the pressure will rise sufficiently to move the valve into an 120

open position. The extent of this rise is dependent on the ratio of the piston heads 29 to that of the valve 9 and this to the weight 35 and upon the mean rate of vertical acceleration to which the body of the car is subjected.

It is apparent that the vibrake affords a positive reactive device which will absorb shocks under practically all reasonable road 10 conditions and thus produce unique results which have not been attained heretofore. Any suitable filling opening may be provided wherever it is found to be most convenient.

15 What I claim is:

1. In shock absorbers, a hydrostatic system, operative connections therefrom to a source of variable accelerations, and means comprising inertia or acceleratively operative valves and cooperative chambers for automatically controlling the alternate phases of such accelerations.

2. In shock absorbers, a system of movable vanes, a multi-chamber in which the 25 vanes have movement, connections from the vanes to a source of variable movement, interconnecting passages between the chambers, and inertia or acceleratively operative valves in such passages.

3. In shock absorbers, a casing, a partition therein, oscillating vanes cooperating with said partition to form two chambers, main passage ways leading from the chambers, a distributing chamber between the 35 passages and connected therewith, a control valve in such connection, an inertia valve adapted to govern access from both the passage ways to the distributing chamber in reverse order from the control valve.

4. In shock absorbers, means for producing forces in either of two directions, means for automatically reducing the resulting movement due to such force in one direc-

tion while permitting it in the other direction.

5. In shock absorbers, a casing, means within the casing responsive to alternately produced movements, a flowing medium within the casing subject to the alternative movements, interconnected passage ways and 50 chambers adapted to segregate the movements in separate compartments, means for permitting the free flow of the transmitting medium in one direction, means for stopping flow in the other direction for a pre-determined period, and automatic means for 55 removing this restriction.

6. In shock absorbers, a casing, a pump system operative therein, an external oil reservoir, a plurality of passages co-acting with 60 the pump system, automatic valves in such passages to control such cooperation, and a check valve between the reservoir and the passages.

7. In shock absorbers a system comprising double acting valves and cooperating chambers which constitute means whose action is variably controlled by interconnected means dependent on the vertical movements of the body of the vehicle with respect to 65 space.

8. In shock absorbers, a system comprising interconnected valves and chambers constituting means to produce forces which will reduce the accelerations of the car body, 75 said forces being dependent upon the vertical accelerations of the vehicle body with respect to space.

9. In shock absorbers, frictional means controlled by the vertical accelerations of 80 the car body with respect to space, and reducing and cooperating means for establishing forces for opposing said accelerations by said means.

In testimony whereof I affix my signature,
EDMUND M. WISE.
